J. J. THACHER

SPINDLE STOP MECHANISM

Filed June 18, 1923

UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

SPINDLE-STOP MECHANISM.

Application filed June 18, 1923. Serial No. 646,202.

To all whom it may concern:

Be it known that I, JOHN J. THACHER, a citizen of the United States, residing at Wethersfield, in the county of Hartford and 5 State of Connecticut, have invented certain new and useful Improvements in Spindle-Stop Mechanism, of which the following is a specification.

This invention relates to drilling machines and particularly to center drilling machines as illustrated in the accompanying drawing. In such machines the operation to be performed is the drilling of a center hole into the end face or faces of a work 10 blank preparatory to mounting the same on the centers of a lathe. Such hole must not only be drilled at the center of the blank but must also be drilled to an exact and accurate depth.

This invention relates particularly to improved means for performing this latter function. Accordingly, the primary object of the invention is to provide improved means for limiting the forward axial movement of a drill spindle whereby the hole drilled thereby is accurately limited to a predetermined depth, such means also preferably being adjustable to permit drilling holes of varying depths.

Another object of the invention is to provide means mounted on the drill spindle sleeve and adapted in operation to limit the forward drilling movement of the spindle by engaging against the work piece, such 30 means also preferably being adjustable to drill holes of varying depths.

Another object of the invention is to provide means mounted on the drill spindle sleeve and adapted in operation to limit the forward drilling movement of the spindle by engaging against a shoulder on the headstock of the machine, such means also preferably being adjustable to drill holes of varying depths.

A further object of the invention is to provide means adapted to limit the axial drilling movement of a drill spindle either by engaging against the work piece being drilled or by engaging against a shoulder 45 on the headstock of the machine, such means comprising an element adapted to be mounted on the drill spindle sleeve in either of two positions, the same in one position limiting the drilling operation by engaging

against the work piece and in the other position by engaging against the headstock of the machine.

With the above and other objects in view, my invention consists in the features of construction and operation set forth in the following specification and illustrated in the accompanying drawing. In such drawing annexed hereto and forming a part of this specification, I have shown one embodiment of my invention, but it will be understood that the invention can be otherwise embodied and that the drawing is not to be construed as defining or limiting the scope of the invention, the claims appended to this specification being relied upon for that purpose.

Referring to the figures of the drawing:

Figure 1 is a fragmentary rear elevation of a center drilling machine embodying my invention.

Fig. 2 is a fragmentary view of Fig. 1 but showing the drill spindles at the limit of their drilling position.

Fig. 3 is a fragmentary cross sectional view taken on line 3—3 of Fig. 1.

Fig. 4 is a fragmentary side elevation of one drill spindle showing my improved spindle stop means mounted in another position.

Fig. 5 is a view like Fig. 4 but showing the drill spindle at the limit of its drilling position.

Fig. 6 is an end view of Fig. 4.

In centering the opposite ends of a plurality of similar blanks preparatory to a turning operation either one of two conditions is to be fulfilled. Either the countersunk centers are to be of predetermined depth in each end regardless of whether the lengths of the blanks are slightly different, or, the distance between the countersunk portions is to be exactly equal for all of the blanks. In the first case, the end faces of the blanks can be utilized as the stops controlling the depth to which the drills may enter. In the second case, some fixed points on the machine must be made use of as the stops. In the present invention, reversible stop members are provided which may be positioned so that they may operate in accordance with either requirement. In one case, they are positioned to abut against the end faces of the blanks and in the other

case they are positioned to abut against the end face of a depression formed in the headstocks carrying the drilling mechanisms.

In the accompanying drawing, I have illustrated a fragmentary portion of the automatic center drilling machine comprised in my copending application, Serial No. 467,056, filed May 5, 1921. In such machine a bed 1 supports respectively on opposite ends thereof a pair of headstocks 2 and 3. Within each headstock is an axially movable sleeve 4 rotatably supporting a drill spindle 5 therein. The spindles are adapted to be rotated from motors 6 through gearing 7.

The work blanks 8 to be drilled are automatically carried from a magazine 9 by a pair of carriers 10 to a pair of cooperating work engaging jaws 11. At this position the blank is centered and held in axial alignment with and between the drill spindles during the drilling operation. All of this mechanism is specifically illustrated and described in my said copending application.

25 The drill spindles 5 are moved to engage the drills 5^a with the work piece as follows: Each sleeve 4 is provided with rack teeth, the rack teeth of one sleeve being engaged by a pinion 12 and the rack teeth of the other sleeve being engaged by a pinion 13. The pinion 13 is operated by a second pinion 14. Connected with each pinion 12 and 14 is a bell crank having arms 15 and 16, a spring pressed plunger 17 being mounted in each arm 16. A loosely mounted lever 18 extends between the arms 15 and 16 and the free ends of such levers are connected to an element 19 by means of links 20. It will be noted that movement of the element 19 in the direction of the arrow in Fig. 1 rotates the pinions 12 and 13 in directions to move the spindles inwardly to the work.

40 The forward end of each sleeve 4 is provided with a collar 21 preferably integral therewith. The outer end of a radially projecting portion of this collar has an opening for receiving the shank 22 of my improved spindle stop member. A set screw 23 threaded into the collar is adapted to secure the shank in the collar. One end of the shank is provided with a head comprising a bifurcated portion 24 and a relatively short portion 25 directly opposite the bifurcated portion.

45 In Figs. 1, 2 and 3 I have illustrated the shank 22 as so mounted in the collar that the head extends forwardly and the bifurcated portion 24 extends inwardly about the drill 5^a. A blank is fed forward to the position shown in Fig. 3 while the drill spindles are in the position shown in Fig. 1. The element 19 is then moved to the left, which operates to engage the drills with the work. As the drills are moved forwardly

under the action of the element 19, the bifurcated portions 24 of the heads come in contact with the work and stop further movement of the drills therein. This position of the parts is shown in Fig. 2. It will be understood that any further movement of the element 19 beyond this limit is taken up at lost motion by the spring pressed plungers 17. It will furthermore be understood that the depth of drilling may be varied by adjusting the shanks 22 in the collar 21.

50 Each headstock 2 and 3 is provided with a recess 26 therein providing a shoulder 27 at the forward end thereof. In Figs. 4, 5 and 6 I have illustrated the shank 22 as so mounted in the collar that the head extends rearwardly and the relatively short portion 25 thereof extends into the recess 26. In Fig. 4 the spindle is shown in the rearward position and in Fig. 5 the spindle is shown at the limit of its forward movement. In the latter position it will be noted that the head portion 25 has engaged against the shoulder 27 and stopped the forward movement of the spindle. The depth of drilling is thus definitely limited as illustrated in Fig. 5. This depth can be varied by adjusting the shank 22 longitudinally in the collar 21.

55 It is believed that the construction and operation of my improved mechanism will be clear from the above description. The spindle stop means may function in either of the two ways illustrated and the depth of drilling in either case may be easily and accurately adjusted by means of the set screw 23.

What I claim is:

1. In a drilling machine, the combination of a headstock, an axially movable sleeve mounted therein, a drill spindle mounted in the sleeve, and means to limit the forward movement of the sleeve and spindle by engaging either against the work piece or against the headstock.

2. In a drilling machine, the combination of a headstock, an axially movable sleeve mounted therein, a drill spindle mounted in the sleeve, means adapted to limit the forward movement of the sleeve and spindle by engaging either against the work piece or against the headstock, and means for adjusting the first said means whereby to vary the said limit of movement.

3. In a drilling machine, the combination of a headstock, an axially movable sleeve mounted therein, a drill spindle mounted in the sleeve, a collar on the sleeve, and an element adapted to be mounted on the collar in either of two positions, the element in one position being adapted to limit the forward movement of the sleeve and spindle in drilling by engaging against the work piece and in the other position being adapted to limit

the same by engaging against the headstock.

4. In a drilling machine, the combination of a headstock, an axially movable sleeve mounted therein, a drill spindle mounted in the sleeve, a collar on the sleeve, an element adapted to be mounted on the collar in either of two positions, the element in one position being adapted to limit the forward movement of the sleeve and spindle in drilling by engaging against the work piece and in the other position being adapted to limit the same by engaging against the headstock, and means permitting the adjustment of the element in a direction axially of the spindle whereby to vary the said limit of movement.

5. In a drilling machine, the combination of a headstock, an axially movable sleeve mounted therein, a drill spindle mounted in the sleeve, the headstock being provided with a recess forming a shoulder, a collar on the sleeve, an element comprising a shank with a head thereon, the shank being adjustably mountable in the collar with the head extending rearwardly and into the recess

or forwardly and inwardly to a position adjacent the spindle axis, the element in the first position being adapted to limit the forward movement of the sleeve and spindle by engaging against the said shoulder and being adapted in the latter position to limit the same by engaging against the work piece, and means permitting axial adjustment of the shank in the collar.

6. In a center drilling machine, the combination of a pair of axially spaced headstocks, an axially movable sleeve mounted in each headstock, a drill spindle mounted in each sleeve, means for supporting a work blank in endwise relation between the drill spindles, and means adjustably mounted on the sleeves and adapted to limit the forward drilling movement of the sleeves and spindles either by engaging against the ends of the blank or by engaging against abutments on the headstocks.

In testimony whereof, I hereto affix my signature.

JOHN J. THACHER.
